DESIGN FOR A NARROW WOVEN FABRIC

Charles S. Wackerman, Bridgeport, Conn., assignor to The American Fabrics Company, Bridgeport, Conn.

Application June 15, 1940, Serial No. 93,030

Term of patent 3½ years

To all whom it may concern:

Be it known that I, Charles S. Wackerman, a citizen of the United States, residing at Bridgeport, in the county of Fairfield, State of Connecticut, have invented a new, original, and ornamental Design for a Narrow Woven Fabric, of which the following is a specification, reference being had to the accompanying drawing forming part thereof.

The drawing shows a face view of a piece of narrow woven fabric embodying my design.

I claim:

The ornamental design for a narrow woven fabric, substantially as shown.

CHARLES S. WACKERMAN.
